WINDOW GRATING

Bernard A. McGuinness, Belmont, Mass.

Application February 14, 1934, Serial No. 711,126

7 Claims. (Cl. 20—71)

This invention relates to window gratings adapted for use to prevent intruders from entering through windows, and it pertains more particularly to a construction in which the bars forming the grating may be readily moved to and removed from the window barring position.

It frequently happens that the occupants of a home or other building may wish to leave the windows open but hesitate to do so for fear that an intruder will enter through an open window. To prevent this bars may be provided across the window but most people object to barred windows as unsightly in appearance.

15 The present invention therefore contemplates a construction in which the window bars may be stored in housings at the sides or top and bottom of the window out of sight when not in use, and may be readily moved to the window barring position when their protection is desired.

One important feature of the invention resides in means for supporting the bars of a window grating for sliding movement from the window barring position to a stored position at one or both sides of the window or at the top and bottom thereof, and in means for locking the bars in the window barring position.

Another important feature resides in a bar receiving housing at one or both sides of a window and in bar supporting guides adjacent the housing and adapted to support the bars for sliding movement from the window barring position to a stored position in the housing.

35 A further feature of the invention resides in bar supporting guides adapted to slidably receive the heads of the bars and provided with spaced pockets along their length to receive said heads and hold the bars in the window barring position, and in key controlled or other means for locking the heads in said pockets.

Other features of the invention and novel combination of parts in addition to the above will be hereinafter described in connection with the accompanying drawing which illustrates one 45 good practical form of the invention.

In the drawing:

Fig. 1 is a front elevation of a window having the window bars of the present invention in the window barring position.

Fig. 2 is a similar view showing the window bars stored at a side of the window.

Fig. 3 is a perspective view of the mechanism of the present invention for supporting and 55 housing the window bars.

Fig. 4 is a transverse sectional view through the upper portion of the window frame of Fig. 1 showing the upper guide rail partly broken away.

Fig. 5 is a front elevation with the upper 60 and lower guide rails shown partly in section.

Fig. 6 is a perspective sectional view of the upper guide rail.

Fig. 7 is a similar view of the lower guide rail; and

Fig. 8 is a top plan view of the lower guide rail.

The window grating of the present invention may be used in the windows of the ordinary home or other building and may be readily installed in windows of various shapes and sizes. The window frame shown, which may be of the usual construction, has the sides 10, top portion 11, and sill or bottom portion 12, and in this frame are slidably mounted the upper sash 75 13 and lower sash 14.

The window grating of the present invention is formed of the independently movable bars 15 that are mounted for sliding movement from the window barring position of Fig. 1 to their 80 concealed or stored position of Fig. 2. These bars are shown as provided with heads 16 at their opposite ends adapted to slide in an upper guide rail 17 and lower guide rail 18, and each guide rail is preferably given the hollow channeled construction shown adapted to slidably 85 embrace the heads.

These guide rails are conveniently made of sheet metal and the upper rail 17 is formed with the spaced upwardly bent edges or ribs 19 having the bar receiving slot 20 between them. The heads 16 may slide upon the ribs 19 as the bars 15 are moved along the guide 17, and in order to retain these bars in the desired spaced relation to each other the head-receiving notches 21 are 95 formed at intervals along the guide rail so that the heads may drop in these notches.

The lower guide rail 18 has the channeled construction best shown in Fig. 3 and the edge portions of the metal strip forming the channel 100 18 are spaced from each other to provide the bar receiving slot 22. The guide rail 18 in the construction shown is provided at intervals along its length with the rectangular holes 23 formed in the lower wall of the channeled rail 18 to 105 receive the correspondingly shaped heads 16. The arrangement is such that when a bar 15 is moved along the guide rails 17 and 18 to the desired position the upper head 16 will drop into a notch 21 and the lower head 16 will drop 110 into a notch 22.

into a hole 23, to hold the bars in the desired spaced relation to each other.

The bars 15 may be readily locked in the position just mentioned by holding the lower

- 5 heads 16 so that they can not be raised out of the holes 23. This is accomplished in the construction shown by providing the locking strip 24 which normally lies inactive within the hollow guide rail 18 at one side of the row of holes 10 23 as shown in Figs. 4 and 7, and when it is desired to lock the bars in the window barring position it is simply necessary to shift the strip 24 in the channel 18 to a position in which it overlies the heads 16 as shown in Fig. 8. The strip 24 may be readily shifted from its inactive position to its active position by providing it with an operating pin or knob 25 that projects upwardly through a diagonal slot 26 formed in the upper wall of the rail 18. The strip 24 is 15 preferably also provided with the inclined surfaces 27 and 28 formed at the opposite edges of the bar and adapted to co-operate with guide pins 29 and 30, respectively, rigidly secured in the guide rail 18.

- 25 The arrangement is such that when the strip 24 is moved in the direction of its length by the knob 25 it will be guided in a diagonal or lateral direction by the engagement of the inclined surfaces 27 or 28 with the fixed pins 29 or 30. The strip 24 may be locked in its bar securing position of Fig. 8 by a key controlled lock 31 secured to the strip 24 and provided with a key actuated bolt 32 positioned to co-operate with a fixed pin 29. The key for the lock is inserted through a hole 33 in the upper wall of the guide 30 18. As long as the lower head of a bolt 15 is held locked in a hole 23 the bolt can not be raised to release its upper end from the corresponding notch 21.

- 35 40 While the mechanism just described constitutes one simple and practical form of means for locking the bars in the window barring position other means to this end may be employed. The locking means may be key or otherwise controlled, and may co-operate with either the upper or lower guide rail or with both of these rails as desired.

- 45 50 The guide rail stock 17 and 18 may be supplied in any desired length so that it may be cut during the operation of installing a guide rail to conform to the width of the window frame to which it is to be secured, and the upper rail 17 is secured to the top portion of the window frame by screws 34 while the lower rail 18 is similarly secured to the window sill 12.

- 55 60 When the bars 15 are not desired in the window barring position of Fig. 1, the locking strip 24 is unlocked and shifted to its inoperative position of Fig. 4 so that the bars may be lifted out of the recesses 21 and 23 and moved along the guide rails to the stored position at each side of the window. It is desirable to conceal the bars while they are stored at the sides of the window and this is accomplished in accordance with the present invention by providing at each side of the window a bar receiving housing 35 which may be formed on sheet metal and given the U-shape in cross-section best shown in Fig. 4. The housing 35 may be cut to the desired length to extend from the upper rail 17 to the lower rail 18 and secured to the window frame by screws 36. The construction illustrated is such that the entire grating including its supporting rails and housings lies within the 70 75 confines of the window frame so as not to pro-

trude beyond the inner face of this frame, and presents a neat appearance.

80 While in the construction shown and described the bars 15 extend vertically of the window and are stored in the housings 35 at the sides thereof, the guide rails 17 and 18 may if desired be mounted at the opposite sides of the window to support the bars in a horizontal position and the housings 35 may be provided at one or both ends of the windows.

85 90 It will be seen from the foregoing that the guide rails 17 and 18 and housings 35 may be readily cut to fit any window and secured in place by the screws 34 and 36. The bars 15 may be cut to the required length and the heads 16 may be riveted or otherwise secured thereto. When the device of the present invention is to be installed in windows of a definite standard size the parts 17, 18 and 35 may be assembled and secured together at the factory to form a rectangle frame adapted to fit the window frame and be secured thereto inside of the sliding sashes.

95 100 When a window is equipped with the grating of the present invention the window may be left wide open either in the day time or at night without the danger of an intruder entering through the open window.

I claim,

1. In combination with a window, a grating therefor made up of independent bars having heads at their opposite ends, hollow channelled guides for said bars secured to the window frame at the opposite ends of the bars and adapted to embrace and slidably support said heads so that the bars may be moved along the guides from the window barring position to a stored position at a side of the window, and means for locking the heads of the bars within the hollow guides at spaced intervals along said guides to hold the bars in the window barring position.

105 110 115 2. In combination with a window, a grating therefor made up of independent bars having heads at their opposite ends, channelled guide rails secured to the window frame at the opposite ends of said bars and adapted to enclose and embrace said heads and support the bars for sliding movement from the window barring position to a stored position at one side of the window, each of said rails being formed with head receiving pockets at spaced intervals along its length, and locking means for locking said heads in said pockets.

120 125 130 135 3. In combination with a window, a grating therefor made up of independently movable bars having heads at their opposite ends, slotted bar supporting guides secured to the window frame at the opposite ends of said bars so that the bar receiving slots in the guides lie in the longitudinal plane of the bars and said guides being adapted to support the bars for sliding movement from a stored position at one side of the window to the window barring position, said guides also being provided along their length with spaced recesses adapted to receive said heads, and means for locking the bar heads in said recesses to fasten the bars in the window barring position.

140 145 150 155 4. In combination with a window, a grating therefor made up of independent bars having heads at their opposite ends, channelled guide rails secured to the window frame at the opposite ends of said bars and adapted to embrace said heads and support the bars for sliding movement from the window barring position to a

stored position, each of said rails being formed with spaced head-receiving pockets, and a locking strip mounted in a channeled rail and movable therein into a position to hold the bar heads in said pockets.

5. In combination with a window, a grating made of bars having bolt heads at their opposite ends, a bar receiving housing at one side of the window, channeled guide rails secured to the window frame at the opposite ends of said bars and adapted to embrace and slidably receive said heads and support the bars for sliding movement from the window barring position to a stored position in said housing, and means 15 for locking the bars in the window barring position.

6. In combination with a window, a grating made of bars, a housing U-shape in cross section and secured to the window frame at one side of the window in the central plane of said bars to house the bars in a stored position, channeled guide rails secured to the window frame at the

opposite ends of said bars and adapted to slidably receive the ends of said bars and support the bars for sliding movement from the window barring position to a stored position in said housing, and means for locking the bars in the window barring position.

7. In combination with a window, a grating therefor made of independently movable bars having heads at their opposite ends, a bar receiving housing at each side of the window, hollow bar supporting guides secured to the top and bottom of the window frame and constructed to embrace said heads and support the bars for sliding movement from the window barring position to a stored position in said housings, means for locking the bars along the guides in the window barring position, and said housings and guides being mounted entirely within the confines of the window frame and positioned to lie in the plane of said bars.
